ALBERT P. McBRIDE, OF INDEPENDENCE, KANSAS.

WIRE ROPE OR CABLE CLAMP.

1,219,015.

Specification of Letters Patent. Patented Mar. 13, 1917.

Application filed July 24, 1914. Serial No. 852,924.

To all whom it may concern:

Be it known that I, ALBERT P. McBRIDE, a citizen of the United States, residing at Independence, in the county of Montgomery and State of Kansas, have invented certain new and useful Improvements in Wire Rope or Cable Clamps, of which the following is a specification.

This invention relates to wire rope or cable clamps of that character for use in drilling oil wells and the like, and my primary object is to produce means whereby the wire rope or cable of a drilling apparatus may be securely clamped or released quickly.

Another object is to produce removable clamping slips or wear plates for the jaws of the clamp, which cannot become accidentally detached from said jaws.

With these objects in view the invention consists in certain novel and peculiar features of construction and combinations of parts as hereinafter described and claimed; and in order that it may be fully understood reference is to be had to the accompanying drawing, in which—

Figure 1, is an elevation of a part of a drilling apparatus equipped with clamping jaws embodying my invention.

Fig. 2, is a top plan view of the jaws.

Fig. 3, is a reduced vertical section taken on the line III—III of Fig. 2.

Fig. 4, is a vertical transverse section taken on the line IV—IV of Fig. 2.

In the said drawing, 1 indicates what is usually known as the main screw, and mounted upon the same for adjustment purposes, is the usual sleeve 2 provided with handles 3, a ball bearing 4 being interposed between the lower end of the sleeve and the collar 5 on the lower end of screw 1, and secured on the sleeve is a cross head 6 provided with openings 7, for the reception of the pendent links 8, a cross pin or bolt 9 securing the links reliably in position.

Pivoted on the lower ends of the links is the clamp, which consists of a pair of members 10, each provided with an upwardly projecting perforated lug 11, for the reception of one of the links 8, the latter being adapted to swing toward and from each other to accommodate pivotal movement of the members 10, one of the same being provided with a series of inwardly projecting lugs 12 and the other member with lugs 13, fitting between the lugs 12. These lugs are

interlocked together like knuckles of a hinge and the pivot bolt 14 extends through them and is engaged at its lower end by a nut 15.

The members 10 forward of the pivot bolt 14 are formed with extended vertical jaws 16, these jaws being of considerably greater length than the depth of the members between their upper and lower faces as shown most clearly in Fig. 3. The lugs 11 rise to a higher plane than the jaws 16.

The jaws 16 are provided with dove-tail grooves 17 for their full length and dove-tailed in said grooves are clamping slips or wear plates 18, provided at their upper ends with outturned arms 19 resting on the upper ends of the jaws and secured thereto by cap screws 20, the inner edges of the slips or wear plates being provided with rounded vertical grooves 21 whereby to receive and effectively grip a drill carrying cable, not shown.

The portions of the members 10 projecting rearwardly or in the opposite direction from the pivotal point of the members to the jaws thereof, are horizontally bifurcated as at 22, as shown in Figs. 3 and 4, and fitting in said bifurcations are blocks 23 provided with vertical trunnions 24 journaled in the overlying and underlying portions of the members, the bearings for the trunnions being composed in part of removable plates 25.

The blocks 23 are provided with aligned openings, that in one of the blocks being smooth as at 25^a, and smaller than the opening 26 in the other block, which opening is threaded to receive the screw 27, which screw has a smooth shank 28, fitting in opening 25.

The smooth shank terminates in a thread engaged by nuts 29, and a washer 30 is interposed between the nuts and the block. The shank 28 also extends through a member 31 of a thrust bearing which also comprises a plate 32 secured rigidly on the angular portion 33 of the screw, and balls 34 interposed between plates 32 and 31, the threaded portion at one end bearing against the plate 32 and being provided at its opposite end with a cross lever or handle 35, by which it can be easily and quickly turned for the purpose of effecting opening or closing movement of the jaws. It is apparent that by the provision of a clamp of this character, that is with the jaws at the opposite side of the pivot from the

handle or lever ends of the members, the clamp can be readily engaged with or disengaged from the wire rope or cable without detaching any part of the appliance, as 5 has been the case heretofore. In this connection it is desired to call attention to the fact that for work of this character, it is essential to guard against accidental slippage of the cable through the clamp, hence 10 all of the appliance for use upon drilling ropes or cables have been arranged so that the rope or cable extends through the clamp at a point between the pivot point and what may be termed the handle or lever end 15 thereof. With my construction, however, I can obtain the requisite gripping or clamping action on the rope by an action similar to that of the ordinary pipe wrench or pliers, the use of the ball thrust bearing and 20 pivoted or swiveled blocks in the bifurcated ends of the members of the clamp guarding against any cramping action which would interfere with the practically instantaneous gripping or releasing of the rope or cable.

25 The operation of the appliance is the same as well known appliances, it being only occasional that it is necessary to operate the screw 27 after the wire rope or cable has been once secured in the clamp. To accommodate the progress of the drill, the attendant operates the sleeve by means of the handle 3 and then lowers the clamp sufficiently to accommodate the progress of the drill, it being of course understood that the 30 turning of the sleeve to lower the clamp does not impart rotation thereto to twist the cable.

If the person in control of the mechanism 40 desires to provide for adjustment of the clamp on the cable without the operation of the sleeve 2, that is by permitting the cable to slip through the clamp to accommodate the progress of the drill, the upper ends of the grooves in the slips will be flared as at 45 36, the flaring of the grooves guarding against injury to the cable as it slides frictionally between the slips, and by dovetailing the latter in the jaws and providing them with the arms 19 resting on and secured 50 to the top of the jaws, precaution is taken against any possibility of the accidental loss of the slips in the well being bored.

From the above description it will be apparent that I have produced a wire rope 55 or cable clamp possessing the features of advantage enumerated as desirable in the statement of the object of the invention, and I wish it to be understood that while I have illustrated and described the preferred embodiment of the invention, I reserve the right to make all changes falling within the spirit and scope of the appended claims.

I claim:

1. A wire rope or cable clamp comprising 65 pivoted members having jaws at one side of the pivot and swiveled blocks at the other side of the pivot, a pair of slips secured in the inner faces of the jaws and provided with opposing semicylindrical grooves and 70 also provided with arms at their upper ends resting and secured upon the upper ends of the jaws, in combination with a screw extending through said blocks and bearing a threaded relation to one of them and a journaled relation to the other and incapable of 75 longitudinal movement through the latter, and a handle for turning said screw.

2. The combination of a pair of members pivoted together between their ends and provided with gripping jaws at one end, and a screw extending through the members at their opposite ends and bearing a swiveled 80 relation thereto; said screw also bearing a threaded relation to one of the members and 85 a journaled relation to the other and a fixed relation as regards endwise movement to the last-mentioned member.

3. The combination of a pair of members pivoted together between their ends and provided with gripping jaws at one end, a block 90 swiveled on each member, a screw extending through said blocks and journaled in one of them and threaded in the other, a thrust bearing between the screw and the inner 95 side of the block in which the screw is journaled, and means secured to the screw and bearing against the outer side of the block in which the screw is journaled.

In testimony whereof, I affix my signature, 100 in the presence of two witnesses.

ALBERT P. McBRIDE.
